DEWAXING OF MINERAL OILS

Leon W. Cook, Beacon, N. Y., assignor to The Texas Company, New York, N. Y., a corporation of Delaware

No Drawing. Application June 25, 1938,
Serial No. 215,877

5 Claims. (Cl. 196—19)

This invention relates to the dewaxing of hydrocarbon oil and particularly to the separation of wax from a mineral lubricating oil.

The invention contemplates the separation of 5 wax from such a wax-bearing oil by the employment of a wax crystal modifying material to facilitate dewaxing by filtration, centrifuging or cold-settling. More particularly, the invention contemplates separating the wax from the oil 10 in the presence of a wax crystal modifying material comprising a chromium soap of a carboxylic acid containing around 10 to 30 carbon atoms. The acids contemplated may be stearic, palmitic, oleic, linoleic, behenic and cerotic acid. 15 Other acids are naphthenic acids and mixtures of naphthenic acid such as obtained in the refining of petroleum. Still other acids that may be employed are abietic, ricinoleic, as well as oxidation products of paraffin wax.

20 It is also contemplated using the chromium soap of these acids alone or in conjunction with a small amount of montan wax. While crude montan wax has been found particularly effective, it is contemplated that the active ingredients thereof may be employed.

I have discovered that chromium soap such as chromium stearate, for example, is unique in its properties as a wax crystal modifying material, particularly since it is highly effective as such 30 in the presence of a wet solvent. By "wet solvent" is meant a dewaxing solvent containing a small amount of water. The chromium soap in this respect is in marked contrast with other metallic soaps.

35 It has been found from actual experience that while the previously known metallic soaps are effective in the presence of a dry or anhydrous dewaxing solvent, they lose a substantial part of their effectiveness in the presence of a wet solvent. In commercial dewaxing plants employing dewaxing solvents it is found difficult, if not economically impossible, to maintain the solvent of the system in an anhydrous condition, the solvent frequently containing as much as 40 1/2% or more of water.

45 Chromium stearate, for example, retains its full effectiveness in the presence of wet solvent, thereby permitting realization of a high yield of dewaxed oil, denser or more compact wax cake, a higher percentage of paraffin in the slack wax, and a slack wax of higher melting point.

50 The chromium compound, therefore, possesses an unexpected advantage over the more commonly known wax crystal modifying materials. While the modifying material is employed in

conjunction with a dewaxing solvent or solvent mixture, various solvents can be used for this purpose, including the well-known and conventional dewaxing solvents and solvent mixtures. Very satisfactory results are secured by the use 5 of a mixture of a wax anti-solvent and an oil solvent, such as a mixture of acetone and benzol, methyl ethyl ketone and benzol, methyl ethyl ketone and isopropyl ether, acetone with benzol and toluol, and the like.

In the case of methyl ethyl ketone-benzol or methyl ethyl ketone-isopropyl ether, generally a proportion of about 40 to 60% methyl ethyl ketone to 60 to 40% benzol or isopropyl ether is 10 satisfactory.

The oil to be dewaxed is diluted with the dewaxing solvent or solvent mixture generally in the dilution ratio of about 2 parts of solvent to one of oil up to about four or five parts of solvent to one of oil, although a smaller dilution 20 ratio may be employed in certain instances.

The soap, or the soap and montan wax, may be dissolved in a small proportion of the lubricating oil at elevated temperatures up to about 300° F. to form a concentrate thereof. This concentrate is then added to the diluted wax-bearing oil charge at a lower temperature of the order of 120° F.

30 In order to realize the maximum effectiveness of the wax crystal modifying material it is advantageous to incorporate the material in the mixture of wax-bearing oil and dewaxing solvent and heat the resulting mixture to a temperature substantially above the temperature of complete solution of the wax and oil in the solvent. The 35 mixture is heated to a temperature of 150° F. and above, usually around 160 to 170° F. in order to condition it for wax separation. The conditioned mixture is chilled to a dewaxing temperature of the order of —10 or —15° F. to precipitate the wax. The precipitated wax is then removed from the cold mixture advantageously by filtration in a continuous rotary filter. The dewaxed filtrate is then stripped to remove the solvent and thus obtain a dewaxed oil having a 40 pour test corresponding substantially to the temperature at which the cold mixture was filtered.

45 In the following examples a solvent refined wax distillate having an A. P. I. gravity of 27.7, a Saybolt Universal viscosity of 86.9 at 210° F., a 50 pour test of 115, and a paraffin content of around 12%, was dewaxed. The solvent consisted of a mixture of 40% methyl ethyl ketone and 60% benzol, and contained 1/2% water. In each case 110 grams of oil were mixed with the solvent in 55

the proportion of four volumes of solvent to one volume of oil. The mixture of wax-bearing oil and solvent was conditioned to a temperature of 170° F. prior to chilling. Thereafter, the mixture was chilled and filtered at a temperature of about -15° F. to remove the wax. The solvent was removed from the resulting filtrate. The results obtained were as follows:

10	Run No. 1	Run No. 2	Run No. 3
Percent chromium stearate.....	0.0	0.25	0.25
Percent montan wax.....	0.0	0.0	0.05
Weight of oil in grams.....	72	84	86
Percent yield of dewaxed oil.....	65.4	76.3	78.2
Filter cake thickness in inches.....	$\frac{3}{4}$	$\frac{7}{16}$	$\frac{3}{8}$
Weight of cake in grams.....	96	55	46
Weight of slack wax in grams.....	30	22	22

As indicated by the foregoing data, when dewaxing in the absence of the modifying material, a yield of 65.4% dewaxed oil was obtained. In the presence of 0.25% chromium stearate (by weight of the wax-bearing oil) the yield was increased to 76.3%. When the soap was used in conjunction with montan wax the yield was somewhat further increased to 78.2%. The presence of soap in the second run reduced the weight of the wax cake to 55 grams, as compared with 90 grams in the absence of any modifying material. The weight of the wax cake was further reduced to 46 grams in the third run when using both soap and montan wax. Thus, the chromium soap, either alone or in conjunction with the montan wax, gave very greatly improved results. The montan wax appears to exert its beneficial action upon the higher melting point constituents of the wax, while the soap exerts its maximum effect upon those constituents

of the wax which are of lower melting point and precipitated at lower temperatures.

The amount of modifying material employed is usually less than 1% by weight of the wax-bearing oil. Satisfactory results are usually secured when using about 0.15 to 0.50% of soap and about 0.02 to 0.25% of the montan wax.

Obviously many modifications and variations of the invention, as hereinbefore set forth, may be made without departing from the spirit and scope thereof, and therefore only such limitations should be imposed as are indicated in the appended claims.

I claim:

1. The method of dewaxing a mixture of wax-bearing oil and dewaxing solvent containing a small amount of water which comprises incorporating in the mixture a small amount of a chromium soap of a higher fatty acid, chilling the mixture to precipitate wax, and separating the precipitated wax from the chilled mixture.

2. The method according to claim 1, in which the chromium soap comprises a soap of a carboxylic acid containing around 10 to 30 carbon atoms.

3. The method according to claim 1, in which the chromium soap comprises chromium stearate.

4. The method according to claim 1, in which the chromium soap comprises a chromium soap of oxidized paraffin wax.

5. The method of dewaxing a mixture of wax-bearing oil and dewaxing solvent containing a small amount of water which comprises incorporating in the mixture a small proportion of montan wax and a chromium soap of a higher fatty acid, chilling the mixture to precipitate wax, and separating the precipitated wax from the chilled mixture.

LEON W. COOK.
